LOUIS M. KOHNER, OF LOS ANGELES, CALIFORNIA.

OIL-BURNER.

1,352,373.

Specification of Letters Patent. Patented Sept. 7, 1920.

Application filed May 21, 1919. Serial No. 298,769.

To all whom it may concern:

Be it known that I, LOUIS M. KOHNER, a citizen of the United States, residing at Los Angeles, in the county of Los Angeles and State of California, have invented new and useful Improvements in Oil-Burners, of which the following is a specification.

This invention relates to an oil burner and pertains to the type of burners especially adapted for use in the fire boxes of cook stoves, ranges, and the like, for burning kerosene and other hydrocarbons of the heavier varieties, and more particularly pertains to the class of liquid fuel burners in which the liquid fuel is delivered to a generating tube disposed above a baffle plate and converted into vapors by the action of flames directed against the generating tube by the baffle plate.

In burners of the above character it is desirable to obviate as far as possible the formation of carbon within the generating tube which is usually caused by excessive feeding of oil to the generator, and it is the object of this invention to provide a construction whereby this may be accomplished.

Another object is to provide means whereby initial generation may be readily and economically effected and also to provide means for collecting such unburned portions of the fuel as may from any cause be discharged from the generator.

Another object is to provide means for shielding the flames against drafts at their point of formation to minimize the danger of their being blown out, and at the same time to provide means for facilitating admixture of air with the hydrocarbon vapors at their point of combustion.

Other objects will appear hereinafter.

The invention is illustrated in the accompanying drawings, in which:

Figure 1 is a view of the burner as seen in side elevation, with portions broken away.

Fig. 2 is a view in perspective illustrating the burner shield removed.

Fig. 3 is a view in end elevation showing the burner with the shield removed.

Fig. 4 is a detail plan view with the generator removed showing the baffle plate, flame spreader, and generating cup.

More specifically, 5 indicates a feed pipe leading from any suitable source of hydrocarbon supply on the upper end of which a

T-connection 6 having oppositely disposed end openings communicating with the terminals of an arched generating tube 7. The connection between the T-coupling and the generating tube is here shown as consisting of a pair of elbow couplings 8 screwed into the T-coupling and having threaded outer ends 9 to receive nuts 10 adapted to be screwed on the ends of the generating tube; the threads on the generating tube and the elbows being right and left, the lower portion of the generating tube including the T-coupling 6 at the elbows 8 form a fuel storage and gasifying chamber. Any other form of connection between the supply pipe and the arched generating tube which will form a fuel storage and gasifying chamber may be provided as may be expedient.

In carrying out my invention the generating tube is disposed at an incline to the horizontal as particularly shown in Fig. 1, and formed on the under side of the connecting end portion of the tube is a discharge orifice 11 arranged so as to discharge downwardly either on the perpendicular or at an incline, the direction of discharge being subject to regulation by adjusting the inclination of the generating tube.

Disposed beneath the generating tube is a baffle plate 12 upon which flames from the burner are projected, this baffle plate being adjustably mounted relative to the generating tube to vary its position in spaced relation to the discharge orifice.

The means here shown for effecting vertical adjustment of the baffle plate embodies a sleeve 13 slidably mounted on the pipe 5 on which the baffle plate is carried. A set screw 14 is screwed in the sleeve 13 to engage the pipe 5 and hold the sleeve and the baffle plate in position.

Formed in the connection between the baffle plate and the sleeve is a generating cup 15 extending beneath the lower portion of the generating tube in such position that on ignition of a generating fluid therein the flames will be directed against the generator at its point of intersection with the feed pipe.

An overflow pipe 16 connects with the side wall of the generating cup and leads to any suitable point of discharge to take care of surplus liquid fuel which may be delivered to the cup.

As a means for affording drainage of such liquid fuel as may be deposited on the baffle plate the latter is disposed at an inclination toward the cup and is formed with surface 5 channels 17 leading to the cup, and for the purpose of spreading the flames directed upon the baffle plate the latter is formed with a central rib 18 having inclined side walls; the rib being disposed between the 10 channels 17 and directly beneath the discharge orifice 11.

As a means for protecting the flames against being extinguished by drafts a shield 19 is provided which is here shown as 15 formed of sheet metal of such shape as to seat upon the outer portion of the generating tube, and as embodying the top wall 20, dependent side walls 21, and an end wall 22; the top wall being formed with down- 20 turned flanges 23 forming with the side walls 21 saddles adapted to seat on the side portions of the generating tube. The side and end walls of the shield are formed with perforations 24 for the admission of air to 25 facilitate admixture of air with hydrocarbon vapors discharged from the generating tube.

In the operation of the invention initial 30 generation may be effected in any desired manner, preferably by igniting fuel in the generating cup so as to heat the lower portion of the generating tube sufficiently to convert hydrocarbon fuel therein into vapors; the fuel being delivered to the generator through any suitable means of control. The vapors formed in the generator are discharged downwardly therefrom and mixed 35 with air beneath the shield, and on being ignited the flames will be directed against the baffle plate and spread thereby. A portion 40 of the flames will be directed against the lower part of the generating tube to continue the generating action.

By adjusting the baffle plate relative to the 45 generator the point of impact of the flames against the generating tube and the intensity of their contact may be varied to suit conditions, and by this arrangement the generator may be subjected to the action of only such 50 flame as is necessary to effect proper vaporization of the hydrocarbon fuel so as to prevent overheating of the hydrocarbon fuel and thereby minimize the formation of carbon within the generator.

55 I claim:

1. A hydrocarbon burner comprising a feed pipe, an arched generating tube communicating with the feed pipe from the opposite sides thereof and inclined relative to 60 the horizontal, said generating tube being formed with a downwardly opening discharge orifice, a baffle plate extending beneath the discharge orifice, and a generating cup arranged beneath the juncture of the

generating tube and feed pipe on which said 65 baffle plate is carried.

2. A hydrocarbon burner comprising a vertical feed pipe, an arched generating tube communicating with the feed pipe from the opposite sides thereof and inclined relative 70 to the horizontal, said generating tube being formed with a downwardly opening discharge orifice, a sleeve adjustable vertically on said feed pipe, and a baffle plate carried by said sleeve and extending beneath the discharge orifice. 75

3. A hydrocarbon burner comprising a vertical feed pipe, an arched generating tube communicating with the feed pipe from the opposite sides thereof and inclined relative 80 to the horizontal, said generating tube being formed with a downwardly opening discharge orifice, a sleeve adjustable vertically on said feed pipe, a baffle plate carried by said sleeve and extending beneath the discharge orifice, and a generating cup formed at the juncture of the sleeve and baffle plate. 85

4. In a hydrocarbon burner, an inclined arched generating tube having a downwardly opening discharge orifice, a baffle plate spaced beneath the discharge orifice, and a perforated shield depending from the arched portion of said generating tube and spaced above the baffle plate. 90

5. In a hydrocarbon burner, a generating 95 tube having a downwardly opening discharge orifice, said tube disposed at an incline to the horizontal, a generating cup arranged at the base portion of said generating tube, a drain pipe connecting with said cup, 100 and a baffle plate disposed beneath the discharge orifice having drain channels leading to the generating cup.

6. In a hydrocarbon burner, a generating tube, a sleeve adjustable vertically relative 105 to said tube, a generating cup formed on said sleeve, and a baffle plate formed on the margin of said generating cup having drain channels leading to said cup and formed with a flame-spreading rib intermediate said 110 channels.

7. In a hydrocarbon burner, a feed pipe, an arched generating tube connected to said feed pipe and having a downwardly opening discharge orifice, a baffle plate spaced beneath said discharge orifice, and a perforated shield depending from said arched generating tube above said baffle plate. 115

8. A hydrocarbon burner comprising a feed pipe, a T-coupling secured to the upper 120 end of said feed pipe, an arched generating tube, an elbow connecting each end of said T-coupling at one end of said arched generating tube, said generating tube being formed with a downwardly discharge orifice, and a 125 baffle plate extending beneath said discharge orifice.

9. A hydrocarbon burner comprising a

feed pipe, a T-coupling secured to the upper end of said feed pipe, an elbow screwed on each end of the T-coupling and formed with a thread at its other end, an arched generating tube threaded at its ends opposite to said thread on the threaded ends of said elbows, a nut coupling screwing on each threaded

end of said arched generating tube and the adjacent threaded end of one of said elbows, said generating tube being provided with a 10 downwardly discharge orifice, and a baffle plate extending beneath said discharge orifice.

LOUIS M. KOHNER.
